Elwin M. Webber
ATTORNEY

UNITED STATES PATENT OFFICE.

MILTON N. WEBBER, OF FORT WAYNE, INDIANA.

RAIL-JOINT CONNECTION.

Application filed July 10, 1922. Serial No. 573,884.

To all whom it may concern:

Be it known that I, MILTON N. WEBBER, a citizen of the United States, residing at Fort Wayne, in the county of Allen and State of Indiana, have invented new and useful Improvements in Rail-Joint Connections, of which the following is a specification.

The invention relates to rail-joint connections and its object is to provide a novel means for connecting track rails at their joints for the purpose of affording a durable and electrically-continuous rail-joint connection which will prevent spreading of the rails and their wearing off at the ends and also prevent electrolysis effects on pipes, etc., in the ground.

The present invention is an improvement on the rail-joint connection described in my previous Patent No. 759,051 and is directed particularly to the bolt which engages the adjacent ends of two rails.

In the accompanying drawings I have illustrated an embodiment of the invention in which—

Figure 1 is a perspective view of two end portions of two rails at their joint having the invention applied thereto; Fig. 2 a transverse sectional view at the meeting ends 30 of the two rails shown in Fig. 1; Fig. 3 a side view of the rails at their joint having the invention applied thereto; Fig. 4 a partly sectional plan view on line 4—4 of Fig. 2; Fig. 5 a perspective view of a portion of a rail adapted for the application of the invention; Fig. 6 an elevational view of one of the fish-plates; Fig. 7 a perspective view of the bolt and Fig. 8 an elevational view of the locking washer.

The track rails 1 and 2 are of the T-shape type and having the usual tread 3, the web 4 and the base flange 5, each end of each rail having a rectangular notch 6 cut therein in such manner that when the adjacent ends 45 of two rails meet, the notches in said ends will aline. Two similar fish-plates 7 and 8 are adapted to be secured to the rails at their meeting ends and upon opposite sides of the rails. Each plate in its lower portion 9 conforms to the opposed surface of the flange 5 of the rail upon which it rests, and the upright portion 10 of each fish plate engages the web of the rail at the lower inner edge of the plate and also at its upper edge which is beaded on the inner face of said portion, as clearly shown in Figs. 1 and 4, so that a

small space is left between the central portion of the fish plate and the web of the rail. Each plate 7 and 8 is apertured at the proper points, as apertures 11, for the reception of the bolts 12 which also pass through apertures in the webs of the rails, suitable lock nuts on the opposite ends of the bolts (not shown) when tightened serving to draw the plates firmly against the rails and locking them in that position. A suitable number of notches 13 are formed in the lower edge of each fish-plate for the reception of the rail spikes 14 by which the rails are secured to the ties 15, and the fish-plates 16 are also further anchored to the rails by said spikes.

A rectangular opening 16 is formed in each fish-plate at approximately the center thereof, so that when two plates are secured 75 to the opposite sides of two meeting rails the opening in each plate will aline with the opening in the opposite plate and aline, also, with the opening in the rails formed by the notches 6. Through these alined openings 80 is passed the bolt 17 having a rectangular body 18 and head 19 and a threaded cylindrical portion 20. A washer 21 having a rectangular central opening 22 is engaged on the portion 20 and a nut 23 milled on its 85 inner face is engaged on the portion 20 and when tightened against the washer draws the bolt firmly into the opening formed by the notches 6, the fit of the bolt and said notches being close. Should the rectangular portion of the bolt 17 project through the fish-plate on the side of the rails opposite the head end of the bolt, the projecting end of the same will engage in the rectangular opening 90 in the washer and hence provide 95 full engagement of the washer upon the fish-plate. Inaccuracies in the thickness of the fish-plates and of the rail web are therefore provided for by the washer and the bolt is firmly held in place, and the bolt 100 having a close fit with the notches in the ends of the rails forms an electrical conductor between the ends of the rails.

What I claim is:

A rail-joint connection comprising two 105 fish-plates secured to opposite sides of two meeting rails, each plate engaging the webs of the rails adjacent the treads and also at the junction point between the said webs and the bases of the rails, said plate also 110 contacting with the surface of the bases of the rails, each plate having a rectangular

opening therein adapted to register with rectangular openings in the meeting ends of the rails, a rectangular bolt forcibly engaged in the registered openings and having a threaded cylindrical portion at one end for the reception of a nut and a washer having a rectangular opening adapted to receive the

rectangular body of the bolt and the washer being adapted to be clamped against the adjacent fish-plate by the nut, each fish plate 10 also having spike receiving notches.

In witness whereof I have hereunto subscribed my name this 6th day of July, 1922.

MILTON N. WEBBER.
